BAG TUBE AND METHOD OF MAKING
SAME

Thomas O. Bancroft, Monroe, La.

Application October 18, 1934, Serial No. 748,855

3 Claims. (Cl. 93—35)

My invention relates to paper bags and their manufacture.

In the manufacture of paper bags for the carbon black industry, difficulties have been encountered that do not occur normally in the uses of paper bags. Carbon black is such a finely divided substance that it will flow or rather sift through open crevices in the bottoms of paper bags whereas coarser materials would not.

10 Numerous attempts have been made to overcome these small leaks. For example, patches of paper have been glued onto the bottoms of paper bags and false bottoms have been pasted on them to prevent leaking. These attempts at solving the difficulty have not been satisfactory, principally because of the increased cost of manufacture.

To overcome leaks in paper bag bottoms, I have directed my inventive thought into redesigning the paper bag bottom itself.

20 My inventive ideas set forth in the instant application are shown and described in this application to multiple ply satchel bottom bags of a type popular in the carbon black industry. However, I do not limit my invention to this type of bag only because the features of my invention are applicable to other types of bags for uses wherever any finely divided material is to be confined.

An important object of my invention is to provide a sift-proof bag.

30 A further object of my invention is to provide a method of forming the bottom of a bag to prevent it from leaking.

A further object of my invention is to provide a method of gluing together plies of bag material preparatory to the formation of a bag.

Other objects and advantages of my invention will be apparent during the course of the following description.

40 In the accompanying drawings, forming a part of this description and in which like numerals are employed to designate like parts throughout the same,

Fig. 1 is a plan view illustrating a gluing step in the formation of my improved bag;

Fig. 2 is a view illustrating a tube forming step in the formation of my improved bag;

Fig. 3 is a view illustrating a bottom slicing step in the formation of my bag;

50 Fig. 4 is a view illustrating the first bottom folding step in the formation of my improved bag;

Fig. 5 is a view illustrating a bottom scoring step in the formation of my improved bag;

55 Fig. 6 is a view illustrating the placing of the

bottom glue tab in the formation of my improved bag;

Fig. 7 is a view illustrating the first bottom closing operation in the formation of my improved bag;

Fig. 8 is a view illustrating the second bottom closing operation, the last step in the formation of my improved bag.

Fig. 9 is a plan view of a multiple ply bag embodying my invention.

In the drawings, wherein, for the purposes of illustration, is shown a preferred form of my invention, numeral 1 designates the tube portion of a bag and numeral 2 designates, generally, the bottom portion.

10 Applicant has noticed that, in multiple ply wall bags, finely divided materials have a way of working between the plies of the bag material exposed on the inner side of the bottom. The finely divided material then finds its way out of the bag 20 between the plies through opening between the plies on the under side of the bag's bottom.

To prevent this type of leak, applicant, in the process of making his improved type of bag, fastens plies A and B together by means of a continuous glue tab 10 (see Fig. 1). The laminated material is then severed on line 13 close to and along side the glue tab 10. The glued ends of the plies are later folded into the bottom of the bag.

25 In the figures illustrating the steps in the process of making a bag according to my invention, arrows are used to indicate the direction of travel of the bag material would take if the operations were performed by a continuous type bag making machine.

30 In the formation of a multiple ply wall tube for bag construction, the first step is the placing of the tab 10 between the plies of bag material. This is accomplished by means of a suitable glue applying means G. The glue tab 10 is shown 40 formed with U shaped portions 11. The tab is made wider at the center. A notch space 12 is left in the center portion of the glue tab. After the glue tab 10 has been applied to one of the plies, the two plies are brought together and 45 stuck. The multiple layer sheet is then cut close to the glue tab by means of a suitable cutting means N. Where more than a double ply bag is desired, additional plies may be superimposed and fastened together by employing additional glue tabs between the added plies of bag material. (See Figure 1).

50 After the plies have been glued together, the laminated sheet is formed into a tube and flattened (see Figure 2), so as to bring pairs of the

U shaped portions 11 of the glue tab 10 together. (See Fig. 2.) It is by means of the U shaped portions of the glue tab 10 that clean paper is left for the bottom cutting knives K to cut through. This feature prevents the bottom cutting knives from gumming up with glue.

In Fig. 3, the bottom slicing step is shown. In standard bag making machines, the bag is grabbed at this stage by means of a gripper P, generally provided with three pins which are passed through the tube. The notch 12 was purposely provided in the glue tab 10 to leave a clean paper space for the center pin to puncture.

15 The position of the outer grabbing pins allows them to puncture parts of the clean paper spaces within the U shaped sections of the glue tab 10.

After the tube 1 has been cut as shown in Fig. 3, the 4 tongues of paper formed in the end of the tube, by the cuts through the end of the flattened tube, may be folded together with parts of the tube proper into a bottom to complete the bag in accordance with standard practices in bag making, well known to those skilled in the art of bag making.

However, I have gone further in my method of bag making, in that I have modified and improved the bottom folding and bottom gluing operations themselves.

30 In Fig. 4, the two side tongues 21 formed in the tube by the cuts, together with parts of the tube stock, are shown creased over toward the center line of the tube. Numeral 22 designates the forward tongue and numeral 23 designates the rear tongue.

In the next operation, the bottom surface is scored on lines 24 to facilitate folding operations. These scores determine the shape and area of the bottom of the finished bag.

40 In the formation of the satchel type bottom on a bag, part of the tube stock, as well as the tongues, must be folded into the bottom.

In a bag of this type, a finely divided substance will find its way out of the bag between the folds 45 of the bottom, if not prevented. The points V (see Figures 7, 8, and 9) mark, in the satchel type bags, openings through which finely divided materials find their way out of the bag between the folds of the folded tube stock brought into 50 the bottom of the bag.

To overcome this difficulty, applicant allows for greater distances X between his score lines 24 and the openings V than the distances Y between the center line Z—Z, and the score lines 55 24, so that the opening V will fall beyond the center line Z—Z, when the final folds are made in the formation of the bag. (See Fig. 5.) This method of folding permits the openings V of the rear flap 23, when folded, to be later completely 60 covered by, and sealed under, part of the bag stock constituting the forward flap 22, the last flap to be folded.

This feature of bottom construction may be accomplished by either varying the location of the score lines 24, when the distance between the cuts C is fixed, or by varying the distance between the cuts, when the locations of the score lines are fixed. It so happens that the demand

of the bag trade for particular sizes of bags pre-determines the locations of these score lines. Therefore, your applicant, to accomplish his end, resorted to the method of varying the distance between the cuts C. An abundance of glue is applied to the forward flap at its points V to assist in sealing the same.

To accomplish my purpose outlined above in satchel bottom bag construction, I fold the side flaps in the conventional manner employed in the manufacture of this type of bag. (See Fig. 4.) The scoring step (Fig. 5) is also carried out according to standard practice to facilitate the final folding operations to follow. In the glue tabbing step, next to follow (see Fig. 6), standard practice is varied from in that the forward and rear tongues 22 and 23, respectively, are made relatively narrower than in standard practice. This fact necessitates the using of relatively narrower U-shaped blue tabs T.

Next in sequence is the first final folding operation, see Figure 7. Here standard practice is varied from in that the entire length of the cuts C, including the openings V, are folded to lie beyond the center line Z—Z of the bottom of the bag.

The next and last step in the formation of the bottom is the final folding operation. (See Fig. 8.) Here the final closing flap 22, the forward flap, is folded to completely cover the entire cut 30 lengths C and openings V of the previously mentioned rear flap 23. Thus the bag is completed.

Fig. 9 shows the bottom features of the above described invention applied to a multiple ply wall bag, comprising tube portion 1a, and base portion 2a. 5a designates points of glue used to lightly tack together the plies of bag material near the bag's mouth to make the bag open properly. In the formation of the bottom of this bag, the steps as outlined in connection with Figures 40 4 to 8 are carried out the same as if only a single-ply material were used.

It is to be understood that the form of my invention shown and described is to be taken as only a preferred embodiment of the same, and 45 that various changes in shape and size may be resorted to without departing from the spirit of my invention or the scope of the subjoined claims.

Having thus described my invention, I claim: 50

1. In the art of making multiple-ply wall bags the step of gluing together sheets of bag material by placing between them glue tabs which include variations that delineate the depth and position for cuts and the step of bringing together the sheets of bag material and sticking the same together after the glue tab has been placed between them.

2. The method as defined in claim 1 wherein the glue tab includes variations to allow for cutting and puncturing of the combined sheets in tube form.

3. A multiple bag tube comprising plies of bag material joined crosswise by one or more glue tabs, the tube being slit at one end, portions of 65 the glue tabs extending crosswise of the tube below the slits.

THOMAS O. BANCROFT.
